DESIGN FOR A CUP FAVOR

Arthur T. Kissinger, Williamsport, Pa., assignor to C. A. Reed Company, Williamsport, Pa., a corporation of Delaware

Application April 19, 1934, Serial No. 51,447

Term of patent 7 years

To all whom it may concern:

Be it known that I, ARTHUR T. KISSINGER, a citizen of the United States, residing at Williamsport, in the county of Lycoming and State of Pennsylvania, have invented a new, original, and ornamental Design for a Cup Favor, of which the following is a specification, reference being had to the accompanying drawing, forming part thereof.

Figures 2 and 3 are front and side views, respectively, of the same.

I claim:

The ornamental design for a cup favor, as shown.
